BEAM CLAMP

Thor Haagensen, New York, N. Y.

Application September 16, 1949, Serial No. 116,089

5 Claims. (Cl. 25—131.5)

1

This invention relates to form clamps or hangers of the character employed for the support of concrete forms from structural steel I-beams.

One of the objects of the invention is to provide a device of this character which will be of simple construction and which will rigidly and firmly grip the flange of the beam and securely support the forms. The invention further contemplates the provision of a hanger or clasp of this character which may be easily fitted in position and adjusted; which will permit the removal and repeated use of its supporting rod; which will permit the maintenance of the clamp parts or gripping elements within the concrete mass without causing the later formation of rust marks on the surface of the concrete, and which will be composed of but few and readily-fabricated parts.

These and other objects are attained by the invention, a more particular description of which will hereinafter appear and be specifically set forth in the claims appended hereto.

In the accompanying drawing, wherein an illustrative embodiment of the invention is disclosed, Fig. 1 is a sectional view of the improved form clamp in engagement with the lower flange of an I-beam, showing the clamp supporting the form boards and with the concrete maintained thereby; Fig. 2 is a view looking at one end of the clamp; Fig. 3 is a top plan view of the clamp in engagement with the lower flange of an I-beam, but with the form boards omitted; Fig. 4 is a horizontal sectional view through the supporting rod just below the upper clamp member or jaw thereon, and Fig. 5 is a view showing a modified form of head on the rod.

The clamp includes a supporting rod 1 which is provided at one end with a threaded end portion 2 on which is threadably and thus adjustably mounted, the two clamp members or jaws 8 and 11 to be presently described. At its other end the rod is provided with a fixed and enlarged head 3 which may be welded or otherwise securely and non-rotatively attached to the end of the rod 1. In the form shown in Figs. 1 to 3 inclusive, said head includes a disk portion 4, having an upper, relatively flat, bearing surface 5 for the support of the form boards shown, for example, at 15 and 16. Extending integrally and laterally from the disk portion 4 is an offset part 6 terminating in a handle shown at 7.

The upper clamp member 8, threadable upon the threads 2 on the rod 1, is in the form of a substantially triangulated or wedge-shaped

2

plate having an under angular face 10 adapted to be maintained against the top of the lower flange of the I-beam 13, as clearly shown in Fig. 1. Arising from the top surface of the clamp member 8 is a vertical fin 9 which enables the clamp member to be manually rotated when placing it in clamping position on the flange of the beam, and also prevents rotative movement of the clamp after the concrete is poured around the same.

The lower or under clamp member is shown at 11, and the same consists of a flat plate which is threadable on the threads 2 and is thereby adjustable on the rod 1 to co-operate with the upper clamp 8 in clamping the flange of the beam 13 between them as shown in Fig. 1. The lower clamping plate 11 is formed at one end with the down-turned lip 12 which facilitates the manual adjustment of this clamp and also holds the same against shifting movement after the concrete has been poured around it.

From the foregoing, the operation of the clamp and form board support will be readily understood. The rod 1 extends through suitable holes 25 or openings in the lower form boards 15 and 16, and which support the side boards 14 in the known manner, and the two clamping jaws 8 and 11 are threadably adjusted on the threaded portion 2 of the rod 1 so that the same securely grip or clamp the lower flange of the I-beam 13 between them. This is always done from above and not from below by manipulation of the handle 7. When the clamp is in position as above described, the concrete 20 is poured in the forms and allowed to harden. When the concrete has hardened, the rod 1 is then removed and drawn out of the concrete by unthreading the rod from the clamp members 8 and 11. The rod 1 and its attached head and handle may then be re-used. The clamp members 8 and 11 are permitted to remain in the concrete mass and the small hole therein resulting from the removal of the rod 1 may then be plugged.

It will be noted that the clamp members 8 and 45 11, remaining within the concrete mass, are so disposed therein that no portions of them are located near the surface of the concrete, but are completely surrounded. This prevents the formation of a large opening at or near the surface of 50 the concrete and the exposure of parts of the clamp members thereat and prevents the formation of rust stains on the surface of the concrete. The clamp members here employed are wholly contained with the concrete mass and located 55 inwardly of the same and thus the objections

found in many clamps in the same category are eliminated.

In the embodiment of the invention shown in Fig. 5, the lower end of the rod 1 is formed with a loop or eye 17 as a substitute for the head 3 and handle 7 thereon. In the latter embodiment the loop 17 may be employed for the support of scaffolding during the building operation, and the rod may be readily rotated for adjustment or removal by a tool inserted through the loop or eye 17.

A further modification may consist in combining the head 3 and handle elements 6 and 7 thereof with the loop 17 so that the loop is disposed below the disk portion 4. With such an arrangement, the combination of operating tool or handle, washer or disk and a loop will be had.

Having described one embodiment of the invention, it is obvious that the same is not to be restricted thereto, but is broad enough to cover all structures coming within the scope of the annexed claims.

What I claim is:

1. A clamp and hanger for structural steel beams embedded in concrete comprising, a rod threaded at one end and provided with a head portion at the other end, a pair of clamp members both independently and both threadably adjustable upon the threaded end of the rod for engaging and clamping the flange of the beam between them, said clamp members remaining in the concrete mass after hardening of the same and being positioned well within the body of the concrete mass and remote from the surface thereof.
2. A clamp or hanger as provided for in claim 1, wherein the head portion is fixedly secured upon the end of the rod and comprises a disk portion for the support of form boards, and an offset handle portion projecting therefrom.
3. A clamp or hanger as provided for in claim 1 wherein the head portion is fixed on the end of the rod and is in the form of a loop or eye.
4. A clamp or hanger for structural steel beams

comprising, a rod threaded at one end and provided with a fixed head portion at its other end, a pair of clamp members independently threadable on said threaded portion of the rod, one of said clamp members being of triangulated form and provided with a longitudinal fin rising from its upper face, the other clamp member being in the form of a flat plate having a laterally-extended lip at one end, said clamp members being adapted to engage and grip the flange of the beam between them.

5. A clamp or hanger for structural steel beams adapted to be embedded in concrete comprising, a rod threaded at one end and provided with a fixed head portion at one end and a threaded portion at its other end, the head portion consisting of a disk having an offset projecting handle, the disk having a flat upper face for bearing against form boards, a pair of clamp members independently threadable upon the threaded portion of the rod, one of the clamp members being of substantially triangulated form and provided with a fin arising from its upper face, the other clamp member being in the form of a flat plate having a downturned end, said clamp members being adapted to engage and clamp the flange of the beam between them and being adapted to remain in the concrete mass remote from the surface thereof after the rod has been removed.
